James H. Conklin of Peekskill, N.Y.

Apignato

R. R. Finch Jr. & R. R. Finch Jr. of same place
Letters Patent N° 468 Dated June 29th 1852.

The schedule referred to in these Letters Patent and making part of the same

To all whom it may concern:

Be it known that I, James H. Conklin of Peekskill, in the County of Westchester, and State of New York, have invented a new design for a cooking stove which I denominate

"The Union Air Light."

and I do hereby declare that the following is a full and exact description of the same reference being had to the accompanying drawings forming part of this specification, in which

Fig. 1. is a siderview of the stove.

Fig. 2. a front view of the same, and

Fig. 3. a half plan of the same.

Fig. 4. is a profile of the front.

Fig. 5. shows the top side of the ornament surrounding the bottom. Similar letters of reference indicate corresponding parts in each of the several figures.

The bottom of the stove is surrounded with an ornament A, which is best shown in Figure 5, but is also shown in Figure 1. The top plate is surrounded by an ogee and fillet B.C (see Figure 4). The side plates have a moulding D, running from the level of the hearth plate upwards, along under the top plate, down the back part and along the lower

Dec. 468

part; The front plate has a running leaf and flower ornament E, in bas relief on each side of the doors. The hearth plate has a moulding round it consisting of a bead and fillet a, and a small cavetto b. The register plate has a small bead c, running round it near its edges, and has two small ornaments d, d.

The large doors of the oven (see Figure 1) are surrounded by a large bead e, and small bead f, with a fillet g, between them, and have a running leaf and flower ornament F, upon them surrounding a scroll ornament G, all in bas relief. The small door of the oven is surrounded by mouldings e, f, g, similar to those of the larger door and has ornaments H, I, similar in character to F, G. The opposite side of the stove has no small oven door but there is an imitation door on the side plate similarly ornamented. The side door of the fire box is surrounded by a bead h, and a sharp fillet i, inside it, and there are bas relief ornaments J, K, upon it nearly similar to H, I. The opposite side plate of the stove has an imitation door which corresponds to the side door of the fire box.

The front doors (see Figure 2) are surrounded by mouldings similar to h, i, and have bas relief ornaments L, M, of similar character with the ornaments on the other doors of the stove.

The feet N, N, are ornamented as shown in Figure 1; they are of the same form and ornamented in the same manner both on the front and sides.

by Letters Patent, is

What I claim as my invention and desire to secure

The design combination and arrangement of the several mouldings & ornaments upon the plates forming the stove and also the configuration of the mouldings & ornaments upon each of the doors and of the feet substantially as described and represented.
